UNITED STATES PATENT OFFICE.

JOHN H. WHITEHOUSE, OF TROY, NEW YORK, ASSIGNOR TO THE LUDLOW VALVE MANUFACTURING COMPANY, OF TROY, NEW YORK, A CORPORATION OF NEW JERSEY.

HYDRANT.

1,021,959.

Specification of Letters Patent.

Patented Apr. 2, 1912.

Application filed April 20, 1909. Serial No. 491,116.

To all whom it may concern:

Be it known that I, JOHN H. WHITEHOUSE, a citizen of the United States, residing at Troy, county of Rensselaer, and 5 State of New York, have invented certain new and useful Improvements in Hydrants, of which the following is a specification.

The invention relates to such improvements and consists of the novel construction 10 and combination of parts hereinafter described and subsequently claimed.

Reference may be had to the accompanying drawings, and the reference characters marked thereon, which form part of this 15 specification.

Similar characters refer to similar parts in the several figures therein.

Figure 1 of the drawings is a central, vertical, longitudinal section of a hydrant 20 embodying my invention, showing the gate in seating position but with the drip-valve yet closed, the gate, wedge-mechanism and drip-valve being shown in side elevation. Fig. 2 is a similar view in full section, 25 showing the gate fully seated, the drip-valve open, and the wedge-members bound together by the stem and collar fixed thereon.

This invention relates more particularly 30 to the class of hydrants wherein the drip-valve is opened by a bodily rising movement of the screw-threaded valve-stem whereby the gate-seating mechanism is actuated. A well known type of hydrant of 35 this class is the Ludlow hydrant.

In hydrants of the class referred to, wherein the gate is forced to its seat by 40 means of wedges, one carried by the gate and the other by the stem, with which it has a screw-threaded connection, the hydraulic pressure upon the face of the gate tends to exert through the wedge carried by the gate a constant lifting force upon the wedge carried by the stem, which lifting force is resisted only by the engagement 45 of the upper end of the stem with a stop mounted upon the upper end of the hydrant-barrel or stand-pipe. In such hydrants, therefore, should the barrel or stand- 50 pipe be broken off, as not infrequently happens, the stem is free to rise under the lifting action of the stem-carried wedge, thus permitting the gate to be automatically opened.

55 The principal object of the present in-

vention is to prevent an upward movement of the stem-carried wedge after the gate has been fully seated, except when accomplished by a rotative movement of the stem. In carrying out my invention, I provide 60 means adapted to be forced by the final rotative movement of the stem in seating the gate into engagement with the gate to positively bind together the gate and the stem-carried wedge. 65

Referring to the drawings wherein the invention is shown in preferred form, 1, represents the barrel or stand-pipe of the hydrant, having an outlet at, 2, and an inlet at, 3, surrounded by a valve-seat, 4, and 70 provided with a drip-opening in its bottom at 5. The valve-stem, 6, is provided with the usual socket-extension, 7, projecting exteriorly through the cap, 8, which socket is adapted to permit a vertical movement of 75 the main stem relatively thereto. A drip-valve, 9, carried by the lower end of the stem, is adapted to close at certain times the drip-opening 5. The lower portion of the stem is screw-threaded at, 10; and 80 mounted upon and fitting said screw-threaded portion of the stem is an upper wedge, 11, adapted to coöperate with a lower wedge, 12, to seat the gate, 13, which carries said lower wedge. The screw-threaded portion of the stem passes loosely 85 through lugs, 14 and 15, projecting from the back of the gate, whereby the gate is loosely interconnected with the upper wedge, 11, and is adapted to be carried thereby to and 90 from a position opposite the seat 4.

The general operation of the hydrant is as follows: To close the hydrant the stem is rotated in a direction to cause the upper wedge, 11, to descend and carry with it the 95 gate, to a point opposite the seat, 4, the drip-valve resting upon its seat surrounding the drip-outlet 5. As the gate reaches a point opposite its seat, the lug, 15, on the back of the gate engages a stop, 16, on the 100 flange, 17, by which engagement downward movement of the gate and the gate-carried lower wedge, 12, is arrested. Further rotation of the stem in the same direction forces the upper wedge, 11, downward between the flange, 17, on the barrel and the lower wedge, 12, on the gate, thereby wedging the gate tightly against its seat; and still further rotation of the stem in the same direction causes the stem to rise bodily, carrying 105 110

with it the drip-valve, 9, to open the drip-outlet 5.

In opening the hydrant the stem is rotated in the reverse direction, first causing 5 the stem to descend until further downward movement is arrested by the engagement of the drip-valve, 9, with its seat, further rotation in said reverse direction causing the wedge, 11, to travel upward along the 10 threaded portion of the stem, to first relieve the pressure of the gate upon its seat, and then to carry the gate upward away from its seat.

As a preferred means for preventing an 15 upward movement of the upper wedge, 11, after the gate is fully seated, except when accomplished by a rotative movement of the stem, I have shown an offset on the stem in the form of a collar, 18, fixed thereon, adapt- 20 ed to be forced into engagement with the lug, 15, on the back of the gate by the final rising movement of the stem in opening the drip-valve after the gate has been fully seated. The collar, 18, is so located upon 25 the stem as to be brought into firm engagement with the lug, 15, by the time the drip-valve is fully opened, and, when in such engagement, said stem and collar serve to firmly bind together the two wedges, so that 30 a wedgewise movement therebetween is impossible. So long as the two wedges are so bound together, an upward movement of the wedge, 11, is rendered impossible, except when accompanied by an upward movement 35 of the wedge, 12, and gate, 13, said parts being in substantially fixed relation to each other, and their movement as a whole being rendered practically impossible by frictional engagement of the wedge, 11, with the 40 flange, 17, and of the gate with its seat. With said wedges so bound together with the gate fully seated, the gate cannot automatically open, even though the whole upper portion of the hydrant-barrel be broken 45 away; and the upper portion of the stem be broken away or bent. A relative movement of separation between the wedges can be accomplished only by first rotating the stem in a direction to move the collar, 18, down- 50 ward away from the gate, which movement is automatically accomplished by the ordinary opening movement of the stem.

For certain purposes of the invention any known means may be employed whereby the 55 wedge-members are positively locked to-

gether by the final rotative movement of the stem in closing the hydrant.

What I claim as new and desire to secure by Letters Patent is—

1. In a hydrant, and in combination, a 60 case; a rotatory and longitudinally movable stem having a screw-threaded portion; a drip-valve carried by the inner end of the stem, adapted to close a drip-outlet; a wedge-member fitting and actuated by the 65 screw-threaded portion of the stem; a gate loosely carried by, and having a wedge-member co-operative with, said stem-actuated wedge-member; a stop on the hydrant-case located in the path of said gate when opposite its seat; and stem-actuated means for binding together the members of the wedge-mechanism by the final rotative movement of the stem inclosing the gate. 70

2. In a hydrant, and in combination, a 75 80 case; a rotatory and longitudinally movable stem having a screw-threaded portion; a drip-valve carried by the inner end of the stem, adapted to close a drip-outlet; a wedge-member fitting and actuated by the screw-threaded portion of the stem; a gate loosely carried by, and having a wedge-member co-operative with, said stem-actuated wedge-member; and stem-actuated means for binding together the members of the wedge-mechanism by the upward movement of the 85 stem which opens the drip-valve. 90

3. In a hydrant, and in combination, a 95 case, a rotatory and longitudinally movable stem having a screw-threaded portion; a drip-valve carried by the inner end of the stem, adapted to close a drip-outlet; a wedge-member fitting and actuated by the screw-threaded portion of the stem; a gate loosely carried by, and having a wedge-member co-operative with, said stem-actuated wedge-member; a stop on the hydrant-case located in the path of said gate when opposite its seat; and an offset from said stem between said drip-valve and said gate engageable with said gate by the final gate-closing movement of the stem, whereby said wedge-members are bound together and the drip-valve is opened. 100

In testimony whereof, I have hereunto set 105 my hand this 19th day of April, 1909.

JOHN H. WHITEHOUSE.
